RAILWAY TRAFFIC CONTROLLING APPARATUS

Earl M. Allen, Swissvale, Pa., assignor to The Union Switch & Signal Company, Swissvale, Pa., a corporation of Pennsylvania

Application July 13, 1940, Serial No. 345,356

10 Claims. (Cl. 246—26)

My invention relates to railway traffic controlling apparatus, and particularly to apparatus for controlling traffic movements over a stretch of single track railway which is connected at each of its ends, by a track switch, with a double track portion.

One feature of my invention is the provision of apparatus controlled by a single manual traffic control device such, for example, as a lever having two control positions, for effecting operation of the track switches at both ends of a single track stretch to a given extreme position and clearing successively located signals for a given direction of traffic movements over the single track stretch if the lever is operated to a given one of its control positions, and for effecting operation of the same track switches to the opposite extreme position and clearing successively located signals for the opposite direction of traffic movements over the single track stretch if the lever is operated to its other control position. Another feature of my invention is the provision of novel and improved apparatus for controlling indication means associated with the signals, switches, track occupancy, and traffic direction control for a stretch of track such as that referred to.

I shall describe one form of apparatus embodying my invention, and shall then point out the novel features thereof in claims.

In the accompanying drawings, Figs. 1A, 1B and 1C, when placed end to end in the order named, with Fig. 1A on the left, constitute a diagrammatic view showing one form of apparatus embodying my invention.

Referring to the drawings, the reference characters 2 and 2a designate the track rails of a stretch of single track railway over which traffic movements may be made in either direction. Adjacent the left-hand end of this stretch of single track, as shown in Fig. 1A of the drawings, which I shall assume is the west end, is a switch 3W leading to a double track portion X. Adjacent the opposite or east end of the stretch of single track, is a second switch 10W leading to a second double track portion Z.

Rails 2 and 2a of the single track stretch, and the rails of the double track portions, are divided by insulated joints 11 to form approach sections 4T and 12T shown in Figs. 1A and 1B, respectively, switch sections 4T and 9T in which switches 3W and 10W, respectively, are located, and other sections 3T, 5T, 6T, 7T, 8T and 10T between the switch sections. Each track section is provided with a track circuit including a suit-

able source of current, such as a battery 13, connected across the rails adjacent one end of the section, and a track relay, designated by the reference character R preceded by the reference character for the associated section, connected across the rails adjacent the opposite end of the section.

Eastbound traffic movements are directed as follows: by a signal 3, from double track portion 10X to the single track stretch over switch 3W in a given position in which it is shown in Fig. 1A and which may be called the normal position; by signals 5 and 7 along the single track stretch; and by signal 9 from the single track stretch to double track portion Z over switch 10W in only the given position in which it is shown in Fig. 1B and which may be called the normal position. Westbound traffic movements are similarly directed as follows: by signal 10 from double track portion Z into the single track stretch over switch 10W in a position opposite to that in which it is shown in Fig. 1B and which may be called the reverse position; by signals 8 and 6 along the single track stretch; and by signal 4 from the single track stretch to double track portion X over switch 3W in only the position opposite to that in which it is shown in Fig. 1A and which may be called the reverse position.

The signals may be of any suitable type such, for example, as color light signals. As shown in the drawings, all signals, except signal 3a for the westbound track of double track portion X and signal 10a for the eastbound track of double track portion Z, comprise three lamps, a green or proceed lamp G, a yellow or caution lamp Y, and a red or stop lamp R. Signals 3a and 10a comprise only a constantly lighted red or stop lamp R.

With the signals controlled as shown in the accompanying drawings, eastbound traffic movements are directed over switch 3W in only its given position in which it is shown, whereas westbound traffic movements are directed over switch 3W in only the opposite position; and eastbound traffic movements are directed over switch 10W in only its given position in which it is shown, whereas westbound traffic movements are directed over switch 10W in only its opposite position.

Operation of switches 3W and 10W from each extreme position to the other, and clearing of the signals for the corresponding direction of traffic movements are effected by a manual traffic control device shown, in Fig. 1C, as a lever V

having a normal position *n*, a given reverse control position *r* to the right, and an opposite reverse control position *f* to the left. Lever V, upon being moved to the *f* position, effects operation of each of the switches 3W and 10W to the position opposite to the given position in which it is shown in the drawings, and effects clearing of the westbound signals. Lever V, upon then being moved to the *r* position, effects operation of each of the switches 3W and 10W to the given position in which it is shown in the drawings, and effects clearing of the eastbound signals.

The means by which lever V effects operation of the switches and clearing of the signals includes a polarized main traffic or lever repeater relay FR which is controlled by pole changer contacts of lever V and by a front contact of a train and switch indication relay 3ASWPR and by a front contact of approach locking relay 10ASR, so that relay FR is energized by current of a given or normal polarity when lever V is moved to its *r* position, and relay FR is energized by current of the opposite or reverse polarity when lever V is moved to its *f* position. Main lever repeater relay FR in turn controls a polarized given or normal control relay NFPR and a polarized opposite or reverse control relay SFPR. Relays NFPR and SFPR in turn control pick-up circuits for corresponding given or normal stick relay NFPSR and opposite or reverse stick relay SFPSR, respectively. Relays FR, NFPR and SFPSR control normal and reverse control circuits which include polarized traffic direction control relays 3FR, 5FR, 7FR and 9FR in series. Signal control relays 3HR, 4HR, 5HR, 6HR, 7HR, 8HR and 10HR, and switch control relays 3WR and 10WR are energized by circuits including polar contacts of the corresponding polarized traffic direction control relays. Signal control relay 9HR is energized by a circuit including a front contact of relay NFPSR and contacts of a switch repeater relay 10WPR.

Traffic direction stick relays 5SR, 6SR, 7SR and 8SR are controlled by corresponding traffic direction control relays, signal control relays and track relays. Front contacts of these stick relays are included in the caution control circuits for signals in the rear of the signals having the control relays by which the stick relays are controlled. The proceed control circuits for signals which have contacts of these stick relays in their caution control circuits are controlled by front contacts of the signal control relays for the next signals in advance, causing the signals which are controlled by the stick relays to be successively cleared after the signals in advance have been cleared in response to a movement of lever V to one of its control positions.

Approach locking stick relays 3ASR, 4ASR, 9ASR and 10ASR are associated with signals 3, 4, 9 and 10, respectively. The circuits for these approach locking stick relays and associated time element devices and time element stick relays are similar to those shown and described for relay 12AS and its associated time element device 12TE and time element stick relay 12TES in Fig. 1-C of a patent No. 2,179,462, granted November 7, 1939, to Henry S. Young, for Railway traffic controlling apparatus. I shall therefore not describe the operation of these relays in detail. The circuits are shown in the accompanying drawings for only relay 3ASR, with which are associated a time element device shown as a thermal relay 3TER, and a time element stick

relay 3TESR. Relays 4ASR, 9ASR and 10ASR are controlled by circuits which are similar to those shown for relay 3ASR.

Switch 10W is operated by a mechanism 10M, the operating circuits for which are indicated as being controlled by switch control relay 10WR. Switch 3W is operated by a similar mechanism 3M which may be similarly controlled by switch control relay 3WR.

Switch control relays 3WR and 10WR are controlled by front contacts of associated track and approach locking relays and by polar contacts of associated traffic direction control relays. A switch repeater relay 3WPR is controlled by contacts operated by switch 3W and by polar contacts operated by relays 3WR and 3FR so that relay 3WPR will become energized only when the contacts operated by the switch and by the switch control relay and traffic direction control relay are all in correspondence. A switch repeater relay 10WPR associated with switch 10W is controlled similarly to switch repeater relay 3WPR.

An eastbound approach repeater relay 3APR and a signal control repeater relay 3RGPPR are controlled over a control conductor 19 and a common conductor WC through asymmetric units *i*1, *i*2, *i*3 and *i*4 by steady positive and negative current and by alternate pulsations of positive and negative current from a suitable source of current such, for example, as a battery Q which has a positive terminal WB, a negative terminal WN, and a middle terminal WC. Asymmetric units *i* may be of the well-known copper oxide rectifier type.

The alternate pulsations of positive and negative current from battery Q are produced by a coding device 3CDR which is constantly operated by current from a suitable source of current having terminals B and C. Coding device 3CDR operates a contact 14 which becomes opened when coding device 3CDR is energized and is then returned to its closed position by a spring 15. Coding device 3CDR therefore closes a second contact 16 alternately in the left and right-hand positions indicated by the dash lines.

Relay 3ASWPR is normally energized by current of a given polarity when approach locking relay 3ASR and switch repeater relay 3WPR are energized while the stretch of single track is unoccupied. Relay 3ASWPR becomes energized by current of the opposite polarity if relay 3WPR becomes deenergized, as when switch 3W, switch control relay 3WR and traffic direction relay 3FR do not agree in position.

Approach indication relays 3AKR and 10AKR are controlled by steady positive and steady negative current and by alternate pulsations of positive and negative current from a source such as a battery Q1, similarly to relays 3APR and 3RGPPR, over a control conductor 124 and a common conductor WC1. A second coding device 10CDR produces alternate pulsations of current similarly to coding device 3CDR already described.

A switch indication relay WKR and a signal indication relay HKR are similarly controlled by steady positive and steady negative current and by alternate pulsations of positive and negative current. Relay WKR will be energized while relay HKR is deenergized if either switch repeater relay 3WPR or 10WPR is deenergized. Relay HKR will be energized while relay WKR is deenergized if either signal control relay 3HR or 10HR is energized. Both relays WKR and HKR

are energized if one or more of the switch sections and the single track sections are occupied while both relays 3HR and 10HR are deenergized and both relays 3WPR and 10WPR are energized.

A traffic direction indication stick relay HKPSR is controlled by relays HKR and WKR.

A train indication stick relay WHKPSR has a pickup circuit controlled by front contacts of both relays HKR and WKR and has a stick circuit controlled by relay HKR.

A polarized traffic direction indication relay FKR is controlled by a back point of relay WKR, by a front contact of relay HKR, and by contacts of lever V.

A track model D is equipped with indication devices including approach indication lamps 3AK and 10AK, signal clear indication lamps 3SK and 10SK, a train indication lamp TK, a switch indication lamp WK, and traffic direction indication lamps EFK and WFK. These indication lamps are controlled by the various indication relays already described.

The main polarized lever repeater relay FR, normal and reverse control relays NFPR and SFPR, traffic direction control relays 3FR, 5FR, 7FR and 9FR, switch control relays 3WR and 10WR, and traffic direction indication relay FKR are all of the type in which the polar contacts remain closed, when the relay is deenergized, in the position to which the polar contacts were last operated.

Having described, in general, the arrangement and control of the various parts of the apparatus embodying my invention, shown in the accompanying drawings, I shall now describe in detail the operation of the apparatus.

The contacts operated by the various relays and other control devices are identified by numbers, each such number having a distinguishing prefix from which it is separated by a dash when the associated contact is shown apart from the relay or other device by which it is operated. The prefix for each of these contact numbers comprises the reference character for the relay or other device by which the associated contact is operated. For example, contact 9TR-45, shown in the circuits for relay 3ASWPR adjacent the symbol for this relay, is identified by the number 45 which is separated by a dash from the prefix 9TR which is the reference character for relay 9TR by which this contact is operated.

As shown in the accompanying drawings, the single track stretch and both double track portions are unoccupied and hence all track relays are energized; traffic control lever V is in its normal or *n* position; the polar contacts of main lever repeater relay FR and of all other polarized relays are in the left-hand position; relays 5HR and 7HR are energized but all other signal control relays are deenergized; the traffic direction stick relays 5SR, 6SR, 7SR and 8SR are deenergized; switch control relays 3WR and 10WR and switch repeater relays 3WPR and 10WPR are energized in the normal direction; relays 3ASR, 4ASR, 9ASR, 10ASR, 3ASWPR and HKPSR are energized; relays 3TESE, 3APR, 3RGPPR, NFPR, SFPR, NFFPSR, SFPSR, FKR, 3AKR, 10AKR, HKR, WKR and WHKPSR are deenergized; coding devices 3CDR and 10CDR are energized; signal 5 is indicating proceed, signal 7 is indicating caution and all other signals are indicating stop; switches 3W and 10W are positioned for eastbound traffic movements.

Signals 3a and 10a are constantly lighted by 73

current from terminals B and C. The red lamps R of all other signals except signals 5 and 7 are lighted by circuits similar to that shown for signal 3, which passes from terminal B, through the back point of contact 3HR-17, and lamp R of signal 3 to terminal C. The caution lamp Y of signal 7 is lighted by a circuit similar to that shown for signal 3, which passes from terminal B, through contact 3HR-17 in its energized position, contact 3HR-18 in the right-hand position, and lamp Y to terminal C. Green lamp G of signal 5 is lighted by a circuit similar to that shown for signal 3, which passes from terminal B, through the front point of contact 3HR-17, contact 3HR-18 closed in the left-hand position, and lamp G to terminal C.

Switches 10W and 3W are in their given or normal position to which they have been operated by a circuit such as indicated for mechanism 10M which includes the front point of contact 10WR-19 and contact 10WR-20 closed in the left-hand position.

Relay 3ASR is energized by its stick circuit passing from terminal B, through contact 3HR-21, front point of contact 25 of relay 3ASR, and the winding of relay 3ASR to terminal C. Relays 4ASR, 9ASR and 10ASR are energized by similar stick circuits.

Relay 3WR is energized by current of normal polarity passing from terminal B, through contact 26 of relay 3FR closed in the left-hand position, winding of relay 3WR, contact 27 of relay 3ASR, contact 28 of relay 4ASR, contact 4TR-29, and contact 30 of relay 3FR closed in the left-hand position to terminal C. Relay 10WR is energized by a similar circuit.

Switch repeater relay 3WPR is energized by a circuit passing from terminal B, through contact 3W-31 closed when switch 3W is in the normal position, contact 32 of relay 3WR closed in the left-hand position, contact 3FR-33 closed in the left-hand position, winding of relay 3WPR, and contact 3W-34 to terminal C. Switch repeater relay 10WPR is energized by a similar circuit.

Relay 3ASWPR is energized in the normal direction by a circuit passing from terminal WB of battery Q, through contact 3ASR-36, front point of contact 3WPR-37, contacts 4TR-38, 3TR-39, 6TR-40, 5TR-41, 8TR-42, 7TR-43, 10TR-44, and 9TR-45, and the winding of relay 3ASWPR to terminal WC.

Traffic direction indication stick relay HKPSR is energized by a stick circuit passing from terminal B, through contact 46 of relay WKR, contact 47 of relay HKPSR, and the winding of relay HKPSR to terminal C.

Eastbound traffic direction indication light EFK is energized by a circuit passing from terminal B, through contact HKPSR-48, contact 49 of relay FKR in the left-hand position, and lamp EFK to terminal C.

I shall assume that the leverman desires to arrange for a westbound traffic movement. He will therefore move lever V to its *f* position, thus completing a circuit for energizing relay FR by current of reverse polarity, this circuit passing from terminal B, through contact 50 of lever V, front point of contact 10ASR-51, front point of contact 3ASWPR-52, winding of relay FR, and contact 53 of lever V to terminal C. Relay FR, upon thus becoming energized by current of reverse polarity, will move its polar armature to the right and complete a circuit for energizing relay SFPR, passing from terminal B, through the front point of contact 54 of relay

FR, contact 55 of relay FR, winding of relay SFPR, and the front point of contact FR-56 to terminal C. With relay SFPR thus energized by current of normal polarity, relay SFPSR will be energized by a circuit passing from terminal B, through contact 57 of relay SFPR, contact 58 of relay SFPR, and the winding of relay SFPSR to terminal C. At the same time, contact 143 of relay FR will be opened, and hence relay NFPR will not become energized.

With relay FR energized in the reverse direction, and with relay SFPSR energized, a circuit will be closed for energizing the traffic direction control relays in the reverse direction, this circuit passing from terminal B, through contact FR-59 in the right-hand position, windings of relays 9FR, 7FR, 5FR and 3FR in series, contact FR-60 closed in the right-hand position, and contact SFPSR-61 to terminal C.

With relays 5FR and 7FR energized in the reverse direction, relays 5HR and 7HR will become deenergized, causing signals 5 and 7 to indicate stop. With relay 3FR energized in the reverse direction, the circuit previously traced for relay 3WPR will be opened at contact 3FR-33, causing relay 3WPR to become deenergized.

With relay 3WPR deenergized, relay 3ASWPR will become energized by current of reverse polarity passing from terminal WC, through the winding of relays 3ASWPR, contacts 9TR-45, 10TR-44, 7TR-43, 8TR-42, 5TR-41, 6TR-40, 3TR-39, 4TR-38, and back point of contact 3WPR-37, to terminal WN of battery Q.

On account of relay 9FR being energized in the reverse direction, relay 10WPR will also be deenergized. With relay 10WPR deenergized, a circuit will be completed for energizing relay WKR, this circuit passing from terminal WC1, through the winding of relay WKR, asymmetric unit 111, conductor 68, contact 3ASWPR-67 closed in the left-hand position, and the back point of contact 10WPR-66 to terminal WN1. When relay 3ASWPR reverses its contacts, relay WKR will remain energized by a circuit passing from terminal WC1, through the winding of relay WKR, asymmetric unit 111, conductor 68, and contact 3ASWPR-67 closed in the right-hand position, to terminal WN1.

With relay 9FR energized in the reverse direction, relay 10WR will now be energized by current of reverse polarity passing from terminal B, through contact 130 of relay 9FR in the right-hand position, winding of relay 10WR, contact 129 of relay 10ASR, contact 128 of relay 9ASR, contact 9TR-127, and contact 126 of relay 9FR closed in the right-hand position to terminal C. With relay 10WR energized in the reverse direction, mechanism 10M will be operated for reversing switch 10W by a circuit indicated as including contact 10WR-19, contact 10WR-20 closed in the right-hand position, and mechanism 10M to terminal C. The mechanism 3M will similarly operate switch 3W to its reverse position, on account of being controlled by relay 3WR now energized in the reverse direction through contacts 26 and 30 of relay 3FR reversed.

Relay WKR upon becoming energized, opens the stick circuit for relay HKPSR, causing this relay to become deenergized. With relay HKPSR deenergized, its contact HKPSR-48 in the circuit previously traced for traffic direction indication lamp EFK will become opened, causing this lamp to be extinguished.

With relay WKR energized, a circuit will be completed for lighting switch indication lamp WK, passing from terminal B, through the front point of contact WKR-69, back point of contact HKR-70, and lamp WK to terminal C.

When switch 3W reaches its opposite or reverse position, relay 3WPR will become energized in the reverse direction by a circuit passing from terminal B, through contact 3W-34 closed 10 in the dash line position, winding of relay 3WPR, contact 3FR-33 closed in the right-hand position, contact 35 of relay 3WR closed in the right-hand position, and contact 3W-31 in the dash line position to terminal C. Relay 10WPR will similarly be energized by current of reverse polarity when switch 10W reaches the opposite or reverse position. With relay 3WPR energized, its contact 3WPR-37 will again become closed, causing relay 3ASWPR to again become energized by current of normal polarity.

With relay 3ASWPR again energized by current of normal polarity, and with relay 10WPR again energized, relay WKR will become deenergized. Although contact 46 of relay WKR is now closed, relay HKPSR will remain deenergized on account of its pick-up circuit being open. With relay WKR deenergized, switch indication lamp WK will now be extinguished.

With relays 3WPR and 3FR both energized by current of reverse polarity, relay 4HR will become energized by a circuit, only a portion of which is shown, including contacts 4TR-71, 3WPR-72, 3WPR-73, 3FR-74, 3FR-75, and the winding of relay 4HR. Relay 4HR, upon becoming energized, will open the stick circuit for relay 4ASR which is similar to the circuit shown for relay 3ASR, thus causing relay 4ASR to become deenergized and open the circuit for relay 3WR at contact 28. With relay 4HR energized, lamp R of signal 4 will become extinguished, and lamp Y or lamp G of this signal will become lighted, in accordance with the conditions of the portions of the control circuit for relay 4HR, which are not in the drawings.

With relay 4HR energized, relay 6HR will become energized by current of normal polarity passing from terminal B, through the front point of contact 83 of relay 4HR, contact 3HR-84, contact 85 of relay 3FR closed in the right-hand position, contacts 4TR-86, 3TR-87, and 6TR-88, contact 89 of relay 5FR closed in the right-hand position, winding of relay 6HR, contact 90 of relay 5FR closed in the right-hand position, contact 91 of relay 3FR closed in the right-hand position, and the front point of contact 92 of relay 4HR to terminal C. With relay 6HR energized by current of normal polarity, red lamp R of signal 6 will become extinguished, and lamp G of this signal will be lighted by its circuit which is similar to the circuit shown for lamp G of signal 3.

With relay 6HR energized, relay 8HR also will become energized in the normal direction by its circuit passing from terminal B, through the front point of contact 93 of relay 6HR, contact 5SR-94, contact 95 of relay 5HR, contact 5FR-96 closed in the right-hand position, contacts 5TR-97 and 8TR-98, contact 99 of relay 7FR closed in the right-hand position, winding of relay 8HR, contact 100 of relay 7FR closed in the right-hand position, contact 5FR-101 closed in the right-hand position, and the front point of contact 102 of relay 6HR to terminal C. With relay 8HR energized, relay 10HR will become energized by current of normal polarity passing

from terminal B, through the front point of contact 103 of relay 8HR, contact 7SR-104, contact 105 of relay 7HR, contact 7FR-106 closed in the right-hand position, contacts 7TR-107, 10TR-108 and 9TR-109, contact 110 of relay 9FR closed in the right-hand position, contact 111 of relay 9HR, contacts 10WPR-112, 10WPR-113, SFPR-114, and SFPR-115, winding of relay 10HR, contact 117 of relay 9FR closed in the right-hand position, contact 7FR-118 closed in the right-hand position, and the front point of contact 119 of relay 8HR to terminal C. With relays 8HR and 10HR energized by current of normal polarity, the red lamps of the corresponding signals will become extinguished, and the green lamps of these signals will be lighted.

Relay 10HR, upon becoming energized, causes relay 10ASR to become deenergized. Relay 10ASR, upon becoming deenergized, causes relay 10WR to also become deenergized. The polar contacts of relay 10WR will, however, remain closed in their reverse positions and hence relay 10WPR will remain energized.

With relay 10HR energized, a circuit will be completed for energizing relay HKR, such circuit passing from terminal WB1, through the front point of contact 10HR-65, front point of contact 10WPR-66, contact 3ASWPR-67 closed in the left-hand position, conductor 68, asymmetric unit 19, and the winding of relay HKR to terminal WC1. With relay HKR energized, relay HKPSR will become energized by its circuit passing from terminal B, through contact 80 of relay HKR, and the winding of relay HKPSR to terminal C. Relay HKPSR, upon becoming energized, completes the stick circuit previously traced for this relay.

With relay HKR energized, a circuit is now completed for energizing relay FKR by current of reverse polarity. This circuit passes from terminal B, through the back point of contact WKR-69, contact HKR-81, contact 82 of lever V, and the upper winding of relay FKR to terminal C. Signal clear indication lamp 10SK will now be energized in multiple with the upper winding of relay FKR. Westbound traffic direction lamp WKF also will now become lighted by a circuit passing from terminal B, through contact HKPSR-48, contact 49 of relay FKR closed in the right-hand position, and lamp WFK to terminal C.

When relay 10ASR becomes deenergized, its contact 10ASR-51 opens at the front point in the circuit traced for relay FR, causing relay FR to become deenergized. A circuit is then completed for retaining relay SFPR in the normal energized condition, this circuit passing from terminal B, through contact 50 of lever V, back point of contact 10ASR-51, back point of contact 54 of relay FR, contact 55 of relay FR, winding of relay SFPR, back point of contact FR-56, and contact 53 of lever V to terminal C.

I shall further assume that a westbound train moves over the westbound route which has been prepared as just described. When the train enters section 12T, relay 12TR becomes deenergized, thereby completing a circuit for energizing relay 10AKR, passing from terminal WB1, through contact 12TR-120, back point of contact 3APR-123, conductor 124, asymmetric unit 15, and the winding of relay 10AKR to terminal WC1. Relay 10AKR, upon becoming energized, completes a circuit for energizing indication lamp 10AK, this circuit passing from terminal

B, through contact 10AKR-125, and lamp 10AK to conductor C.

When the train enters section 9T, the circuit for relay 10WR becomes opened at another point by contact 9TR-127. Relay 9TR, upon becoming deenergized, opens, at its contact 9TR-109, the circuit previously traced for relay 10HR, causing lamp G of signal 10 to now be extinguished and lamp R to again become lighted. With relays 10HR and 9TR deenergized, a circuit is completed for energizing relay 10ASR, which is similar to one of the pick-up circuits shown for relay 3ASR. Relay 9TR, upon becoming deenergized, also opens, at its contact 9TR-45, a circuit previously traced for relay 3ASWPR.

With relay 3ASWPR deenergized and relay 10ASR energized, a second circuit is now complete for retaining relay SFPR energized, which is the same as the circuit previously traced for retaining this relay energized except including the back point of contact 3ASWPR-52 and the front point of contact 10ASR-51 instead of only the back point of contact 10ASR-51. With relay 3ASWPR deenergized, a stick circuit is completed for relay SFPSR, this circuit passing from terminal B, through contact 57 of relay SFPR, contact 3ASWPR-157, contact 158 of relay SFPSR, and the winding of relay SFPSR to terminal C.

With relay 3ASWPR deenergized and relay 10HR now deenergized, a circuit is completed for energizing relay HKR by normal pulses of current when contact 62 of coding device 10CDR moves to the dash line position shown to the left, this circuit passing from terminal WB1, through contact 62 closed in the left-hand position, contact 3ASWPR-63, back point of contact 3RGPPR-64, back point of contact 10HR-65, front point of contact 10WPR-66, contact 3ASWPR-67 closed in the left-hand position, conductor 68, asymmetric unit 19, and the winding of relay HKR to terminal WC1. A similar circuit energizes relay WKR by pulses of negative polarity each time that contact 62 of coding device 10CDR moves to the right-hand position. Relay HKPSR now remains energized through contact 80 of relay HKR.

With both relays WKR and HKR energized, a circuit is completed for energizing relay WHKPSR, this circuit passing from terminal B, through the front point of contact WKR-69, front point of contact HKR-70, and the winding of relay WHKPSR to terminal C. Relay WHKPSR, upon becoming energized, completes a stick circuit passing from terminal B, through contact HKR-131, contact 132 of relay WHKPSR, and the winding of relay WHKPSR to terminal C.

With relay WHKPSR energized, train indication device TK becomes lighted by a circuit passing from terminal B, through contact 133 of relay WHKPSR, and indication lamp TK to terminal C. With relay WKR energized, the circuit previously traced for lamp 10SK is opened at the back point of contact WKR-69, causing lamp 10SK to be extinguished. The reverse energizing circuit for relay FKR is also now opened at the back point of contact WKR-69, but polar contact 49 of relay FKR will remain closed in the reverse position, and hence lamp WFK will remain lighted.

Relays 10TR, 11TR and 8TR become successively deenergized as the train proceeds westward, causing relay 3ASWPR to remain deenergized

due to the successive opening of contacts 10TR-44, 7TR-43 and 8TR-42.

Relay 8TR, upon becoming deenergized, completes a circuit for energizing relay 8SR, this circuit passing from terminal B, through contact 7FR-134 in the right-hand position, contact 8TR-135, front point of contact 136 of relay 8HR, and the winding of relay 8SR to terminal C. Since relay 8HR is of the slow-release slow-pick-up type, relay 8SR will close its front contact 137 before relay 8HR releases its front contact 136. A stick circuit is thus completed for relay 8SR which is the same as its pick-up circuit just traced except that it includes contact 137 of relay 8SR instead of the front point of contact 136 of relay 8HR. When contact 136 of relay 8HR closes at its back point, a second stick circuit is completed for relay 8SR, this circuit passing from terminal B, through contact 7FR-134 closed in the right-hand position, back point of contact 136 of relay 8HR, contact 137 of relay 8SR, and the winding of relay 8SR to terminal C. On account of relay 8HR being deenergized, the green lamp of signal 8 will be extinguished and the red lamp will become lighted.

With relay 8SR energized and relay 8HR deenergized, a circuit will be complete for energizing relay 10HR by current of reverse polarity when the train leaves section 7T, this circuit passing from terminal B, through contact 159 of relay 8SR, back point of contact 119 of relay 8HR, contact 7FR-118 closed in the right-hand position, contact 117 of relay 9FR closed in the right-hand position, winding of relay 10HR, contacts SFPR-115, SFPR-114, 10WPR-113, and 10WPR-112, contact 111 of relay 9HR, contact 110 of relay 9FR closed in the right-hand position, contacts 9TR-109, 10TR-108, and 7TR-107, contact 7FR-106 closed in the right-hand position, contact 105 of relay 7HR, contact 7SR-104, and the back point of contact 103 of relay 8HR to terminal C. The red lamp of signal 10 will now become extinguished and the yellow lamp will become lighted.

With relay 10HR energized, relay WKR will be deenergized and relay HKR will be retained in the energized condition by its circuit previously traced through the front point of contact 10HR-65. Relay WHKPSR will therefore be retained in the energized condition by its stick circuit previously traced, causing indication lamp TK to remain lighted. As the train continues westward, the circuit for relay 3ASWPR will become further opened at contacts 5TR-41 and 6TR-40.

When the train enters section 6T, relay 6SR will become energized and will be retained energized by circuits which are similar to the circuits traced for relay 8SR when the train enters section 8T.

When the train leaves section 5T, a circuit will be completed for energizing relay 8HR by current of reverse polarity, this circuit passing from terminal B, through contact 160 of relay 6SR, back point of contact 102 of relay 6HR, contact 5FR-101 closed in the right-hand position, contact 100 of relay 7FR closed in the right-hand position, winding of relay 8HR, contact 99 of relay 7FR closed in the right-hand position, contacts 8TR-98 and 5TR-97, contact 5FR-96 closed in the right-hand position, contact 95 of relay 5HR, contact 5SR-94, the back point of contact 93 of relay 6HR to terminal C. With relay 8HR thus energized, relay 10HR will become energized in the normal direction by a cir-

cuit previously traced. Signal 8 will now display the caution indication, and signal 10 will display the proceed indication.

As the train proceeds through sections 3T and 4T, the circuits for relay 3ASWPR will become further opened successively at contacts 3TR-39 and 4TR-38. With relay 4TR deenergized, the circuit for relay 4HR will become opened at contact 4TR-31. With relays 4TR and 4HR now deenergized, relay 4ASR will become energized.

When the train leaves section 4T, relay 6HR will become energized in the reverse direction by a circuit which is the same as the circuit previously traced for this relay except including the back points of contacts 83 and 92 of relay 4HR instead of the front points of these contacts. With relay 6HR thus energized, relay 8HR will again become energized by current of normal polarity by its circuit previously traced, and hence lamp G of signal 8 will now become lighted. With relay 6HR now energized by current of reverse polarity, the Y lamp of signal 6 will become lighted.

When the train leaves section 4T, relay 3ASWPR will again become energized in the normal direction by its circuit previously traced.

If lever V is left in its *f* position, relay SFPR will be retained in the normal energized condition by its circuit previously traced through the back point of contact 10ASR-51, and relay SFPSR will also be retained in the energized condition by its pick-up circuit. If, now, while relay 10ASR is deenergized, or if after relay 3ASWPR becomes deenergized due to a second westbound train, the leverman should attempt to reverse the direction of traffic movement by moving lever V to the *r* position, he will energize relay SFPR by current of reverse polarity passing from terminal B, through contact 161 of lever V, back point of contact FR-56, winding of relay SFPR, contact 55 of relay FR, back point of contact 54 of relay FR, back point of contact 3ASWPR-52 and the front point of contact 10ASR-51, or the back point of contact 10ASR-51, and contact 162 of lever V to terminal C. Relay SFPSR will therefore now be deenergized because contact 57 of relay SFPR will open. Relay NFPR cannot become energized on account of contact 143 of relay FR being open. The reverse energizing circuit traced for relays 3FR, 5FR, 7FR and 9FR will thus be opened at contact SFPSR-61, but the normal energizing circuit for these relays will not be closed through contacts FR-59 and FR-60 in the left-hand position, nor through a front contact shown for relay NFPR. It is therefore impossible to reverse the traffic direction control while either relay 10ASR or relay 3ASWPR is deenergized.

I shall next assume that the route shown in the drawings for westbound traffic movements is again unoccupied, and that the apparatus is arranged as already described for a westbound traffic movement. If, now, after a westbound train passes signal 10, the leverman desires to hold signal 10 at stop but to permit the westbound train to continue its movement to double track portion X, he will move lever V to the *n* position, thereby deenergizing relays FR and SFPR. The circuit for relay 10HR will therefore be opened at contact SFPR-114 as well as at contacts of track relays. Relay SFPSR will, however, be retained in the energized condition by its stick circuit previously traced. The circuit for the traffic direction control relays will therefore remain closed through contact SFPSR-61.

Relay 4HR, which includes front contact 3FR-14, will therefore remain energized, causing signal 4 to continue to display a proceed or caution indication.

I shall now assume that the leverman desires to cause signal 4 to indicate stop in the face of an approaching westbound train, as well as to keep signal 10 from clearing after the train has entered the single track stretch. He will therefore move lever V to the r position, thus energizing relay SFPR in the reverse direction by the circuit previously traced, thereby opening contact 57 of relay SFPR and so deenergizing relay SFPSR and causing relay 3FR to become deenergized and open the circuit for relay 4HR at contact 3FR-14.

I shall again assume that the leverman desires to permit a westbound train to proceed as far as signal 4 only, but that the train is still on double track portion Z. He will therefore move lever V to the f position to arrange the switches and clear the westbound signals. After indication lamp 10SK becomes lighted, he will move lever V to the r position, thereby energizing relay SFPR in the reverse direction by the circuit previously traced through the back point of contact 10ASR-51, and deenergizing relay SFPSR. Relay 10HR will now be retained in the energized condition by a stick circuit which is the same as the circuit previously traced for this relay except including contact 116 of relay 10HR instead of contact SFPR-115. Signal 10 will therefore be retained in the clear condition, but signal 4 will be caused to indicate stop on account of the opening of contact SFPSR-61 in the circuit for the traffic direction control relays causing contact 3FR-14 to become opened in the circuit for relay 4HR.

I shall now assume that all parts of the apparatus are again in the condition shown in the accompanying drawings, and that the leverman desires to arrange the switches for a westbound traffic movement but to keep signal 10 indicating stop. He will therefore move lever V to the f position as before, and as soon as switch indication lamp WK becomes lighted, he will return lever V to the n position, thereby deenergizing relays SFPR and SFPSR. With relay SFPSR deenergized, the circuit for the traffic direction control relays will be opened, thus preventing relay 4HR from becoming energized, and the opening of contact SFPR-114 will prevent relay 10HR from becoming energized. Signals 4 and 10 will therefore remain in the stop condition. Since, however, the polar contacts of relays 3FR and 9FR remain in the condition corresponding to the last direction of energization, relays 3WR and 10WR will remain energized in the reverse direction, causing the corresponding switches to be operated to the reverse position. Relay 6HR will now be energized in the reverse direction and relay 8HR will be energized in the normal direction, causing signal 6 to indicate caution and 8 to indicate proceed, respectively.

The operation of the apparatus has been described for typical westbound traffic movements. It is believed that in view of the description of these examples, the operation of the apparatus for corresponding eastbound traffic movements or for any other possible traffic movements will be readily understood by referring to the accompanying drawings.

Although I have herein shown and described only one form of apparatus embodying my invention, it is to be understood that various changes

and modifications may be made therein within the scope of the appended claims without departing from the spirit and scope of my invention.

Having thus described my invention, what I

claim is:

1. Traffic controlling apparatus for a stretch of single track railway connected by a track switch at each of its ends with a double track portion, comprising in combination, a signal for each of said double track portions for governing traffic movements from the corresponding double track portion to said stretch of single track, a signal for each end of said stretch of single track for governing traffic movements from the corresponding end of said stretch of single track to the adjacent double track portion, a manual control device, means responsive to a given operation of said manual control device for operating each of said switches to a given extreme position and for clearing the signals for a given direction of traffic movements, means responsive to a second operation of said manual control device for operating each of said switches to the opposite extreme position and for clearing the signals for the opposite direction of traffic movements, and means responsive to a third operation of said manual control device following either said given or said second operation for cancelling the clear indication of one of the signals and retaining the clear indication of the other signal for the direction of traffic movements which corresponds to the lever operation next preceding said third operation.

2. Traffic controlling apparatus for a given stretch of railway track, including in combination, a manual control device, a polarized main traffic relay, a normal control relay, a reverse control relay, means controlled by a given operation of said manual control device for energizing said main traffic relay by current of a given polarity, means controlled by a second operation of said manual control device for energizing said main traffic relay by current of the opposite polarity, means controlled by said main traffic relay upon becoming energized by current of said given or said opposite polarity for effecting energization of said normal or said reverse control relay respectively, means controlled by a train occupying said stretch of railway track for deenergizing said main traffic relay and then in cooperation with said given or said second operation of said manual control device retaining said normal or said reverse control relay energized, and means responsive to energization of said normal or said reverse control relay if polar contacts of said main traffic relay are in corresponding positions for directing traffic movements in a given direction or the reverse direction respectively over said stretch of track.

3. Traffic controlling apparatus for a given stretch of railway track, including in combination, a manual control device, a normal control relay, a reverse control relay, means responsive to said manual control device in a given operated position for energizing said normal control relay if said stretch of track is unoccupied, means responsive to said manual control device in a second operated position for energizing said reverse control relay if said stretch of track is unoccupied, means responsive to said manual control device in its given or its second operated position if said stretch of track is occupied for energizing said normal

control relay or said reverse control relay respectively if said manual control device was last moved to the corresponding operated position while said stretch of track was unoccupied, and means responsive to energization of said normal or said reverse control relay if a corresponding contact controlled by said manual control device is closed for directing traffic movements in a given direction or the reverse direction respectively over said stretch of track.

4. Traffic controlling apparatus for a given stretch of railway track, including in combination, a manual control device, a polarized normal control relay, a polarized reverse control relay, means responsive to said manual control device in given and reverse control positions for energizing said polarized normal or reverse control relay respectively, a normal and a reverse stick relay, pick-up circuits for said normal and reverse stick relays controlled by a normal polar and a front neutral contact of said normal and reverse control relays respectively, a stick circuit for each of said stick relays controlled by a normal polar contact of the corresponding normal or reverse control relay and by a contact which is closed in response to a train in said stretch of track, and means including a front contact of said normal control relay or a front contact of said reverse stick relay for energizing traffic controlling apparatus for a given direction or the opposite direction respectively over said stretch of track.

5. Indication control apparatus for a stretch of railway track including a track switch and provided with a given signal for governing traffic movements in a given direction over said stretch and also provided with a reverse signal for governing traffic movements in the opposite direction over said stretch, comprising in combination, a signal indication relay, a switch indication relay, means for energizing only said signal indication relay if one of said signals is controlled to direct a traffic movement over said stretch of track, means for energizing only said switch indication relay if said switch is being operated from one of its extreme positions to the other, means for energizing both said signal and switch indication relays if said stretch of track is occupied by a train and if said signals are controlled to indicate stop and if said switch occupies either of its extreme positions, switch indication energizing means controlled by a front contact of said switch indication relay in series with a back contact of said signal indication relay, signal indication energizing means controlled by a back contact of said switch indication relay in series with a front contact of said signal indication relay, and track occupancy indication energizing means controlled by a front contact of said switch indication relay in series with a front contact of said signal indication relay.

6. Indication control apparatus for a stretch of railway track including a track switch and provided with signal means for governing traffic movements over said stretch, comprising in combination, a signal indication relay, a switch indication relay, means for energizing only said signal indication relay in response to a given signal control condition, means for energizing only said switch indication relay in response to a given switch control condition, means for energizing both said signal and said switch indication relays in response to a train on said stretch and to a second signal control

condition and a second switch control condition, signal indication means controlled by a front contact of said signal indication relay in series with a back contact of said switch indication relay, switch indication means controlled by a front contact of said switch indication relay in series with a back contact of said signal indication relay, and train indication means controlled by a front contact of said signal indication relay in series with a front contact of said switch indication relay.

7. Indicating control apparatus for a stretch of railway track including a track switch and provided with signal means for governing traffic movements over said stretch, comprising in combination, a signal indication relay, a switch indication relay, means for energizing only said signal indication relay in response to a given signal control condition, means for energizing only said switch indication relay in response to a given switch control condition, means for energizing both said signal and said switch indication relays in response to a train on said stretch, a traffic direction indication stick relay, a pick-up circuit for said traffic direction indication stick relay controlled by a front contact of said signal indication relay, a stick circuit for said traffic direction indication stick relay controlled by a front contact of said signal indication relay, a switch indication relay controlled by a back contact of said switch indication relay, a traffic lever having a given and a reverse control position for controlling said signal means and said track switch for directing traffic movements in a given and a reverse direction respectively over said stretch, a polarized indication relay having a polar contact which when this relay becomes deenergized will remain closed in the position corresponding to the last direction of energization of this relay, a given and a reverse control circuit for said polarized indication relay controlled by said traffic lever in its given and reverse positions respectively and by a front contact of said signal indication relay in series with a back contact of said switch indication relay, and a given and a reverse traffic direction indication device controlled by the polar contact of said polarized indication relay in given and reverse positions respectively corresponding to its control circuits and by a front contact of said traffic direction indication stick relay.

8. Indication control apparatus for a stretch of railway track including a track switch and provided with signal means for governing traffic movements over said stretch, comprising in combination, a signal indication relay, a switch indication relay, means for energizing only said signal indication relay in response to a given signal control condition, means for energizing only said switch indication relay in response to a given switch control condition, means for energizing both said signal and said switch indication relays in response to a train on said stretch, a train indication stick relay, a pick-up circuit for said train indication stick relay controlled by a front contact of said switch indication relay in series with a front contact of said signal indication relay, a stick circuit for said train indication stick relay controlled by a front contact of said signal indication relay, and a train indication device controlled by a front contact of said train indication stick relay.

9. Indication control apparatus for a stretch of railway track including a track switch and provided with signal means for governing traffic

movements over said stretch, comprising in combination, a pair of conductors, signal indication control apparatus responsive only to current of normal polarity and switch indication control apparatus responsive only to current of reverse polarity each connected across said conductors, a signal indication control contact having a normal position and having a second position to which it is operated if said signal means is controlled to direct a traffic movement over said stretch of track, a switch indication control contact having a normal position and having a second position to which it is operated in response to a given condition of said switch, means controlled by said signal and switch indication control contacts in the second position for supplying current of normal or reverse polarity respectively to said pair of conductors, and means controlled by a train responsive contact and by both of said signal and switch indication control contacts in the normal position for supplying current of normal and reverse polarity alternately to said pair of conductors if a train occupies said stretch of track.

25

10. Indication control apparatus for a stretch of railway track including a track switch and provided with signal means for governing traffic movements over said stretch, comprising in combination, signal indication control apparatus, switch indication control apparatus, a signal indication control contact having a normal position and having a second position to which it is operated if said signal means is controlled to direct traffic movements over said stretch of track, a switch indication control contact having a normal position and having a second position to which it is operated in response to a given condition of said switch, means controlled by said signal and switch indication control contacts in the second position for energizing said signal indication control apparatus and said switch indication control apparatus respectively, and means controlled by a train responsive contact and by both of said signal and switch indication control contacts in the normal position for energizing both said signal indication control apparatus and said switch indication control apparatus.

EARL M. ALLEN.
